UNITED STATES PATENT OFFICE.

JOSEPH WHITMAN BUELL, OF WASHINGTON, DISTRICT OF COLUMBIA; WANDA A. BUELL, EXECUTRIX OF SAID JOSEPH WHITMAN BUELL, DECEASED, ASSIGNOR TO BUELL SIGNAL AND TRAIN CONTROL COMPANY, INCORPORATED, A CORPORATION OF VIRGINIA.

DUALISTIC CAB SIGNAL AND AUTOMATIC TRAIN-CONTROL SYSTEM.

Application filed September 14, 1921. Serial No. 500,673.

To all whom it may concern:

Be it known that I, JOSEPH WHITMAN BUELL, a citizen of the United States, residing at the city of Washington, in the District of Columbia, have invented certain new and useful Improvements in a Dualistic Cab Signal and Automatic Train-Control System, of which the following is a specification.

- 10 This invention relates to a dualistic cab signal and automatic train control system, that contemplates combining the general type of system disclosed in reissue patent, numbered 14,676, dated June 24th, 1919, 15 with that type of system disclosed in my co-pending United States application for Letters Patent, serial numbered 452,695 and filed March 16th, 1921.

Before dealing with or describing the actual system and apparatus, a good deal of ground will be cleared if certain aspects of the invention are first dealt with in more or less general terms.

In order to understand the nature and scope of the present invention with reference to its fundamental characteristics, it will first be considered in relation to the principle of arrangement of the circuits and control elements, as a means of effecting a 30 true combination.

In this general class of devices, it is necessary to employ on a locomotive, an electro-magnet governing means for controlling a signal giving device and normally holding closed an air vent in the brake system, as long as current flows through said magnet and upon the failure thereof to cause the production of a signal and the application of the air brakes.

40 One of the main objections to the employment of a single system of contrivances between the said magnet governing means and the track apparatus, for its control and operation, has been that when one of the 45 members of the system becomes deranged it necessarily incapacitates the whole system and a locomotive thus equipped has to proceed throughout the rest of its run with sole reliance on the roadside signals.

50 The present invention therefore contemplates multiple control and operation of the magnet governing means, by the establishment and interruption of the current

flowing through said magnet by reason of the joint control or effect of a composite 55 or duplicate means that is interposed between said magnet and the respective track circuits encountered.

To the end of providing a dualistic or composite system, one branch thereof is 60 arranged in operative relation to said electro-magnet and comprises two normally interlinked circuit members, working on the closed circuit principle, one of which includes said electro-magnet, while the other 65 is brought into direct union with the all rail track circuit for control thereby at traffic control points; said control being effected in this branch of the system by the introduction and withdrawal of a point of 70 resistance, in the track connected circuit, under the influence of a safety shunt controlled by said track circuit.

The other branch of said dualistic system contemplates the employment of a controlling and operating apparatus, in which one element comprises a comparatively slow acting mechanically operated means, such as a circuit breaker, controlled in its movement by a shoe engaging with a ramp, and which serves to positively interrupt the above mentioned circuits at such points, every time said circuits pass those points, were provision not made, under safety conditions, for introducing momentarily 85 into the combination, a normally incomplete circuit by closing the same under the influence of a second safety shunt and the controlling track circuit, to quickly effect a shunt or compensating pathway across 90 those portions of the interlinked circuits about to be broken by the mechanically operated means, to thereby preserve the integrity of those circuits so far as the mechanically operated means is concerned. 95

In other words this invention contemplates combining one electrical system of control with an electro-mechanical system of control, each of which constitutes an adequate means for train control at traffic control points, so that in the event of one of said sub-systems becoming deranged, it may be cut out and reliance be placed in safeguarding the train on the other sub-system, without causing inconvenience or 105 delay.

By reason of such a principle of circuit and control arrangement there is provided a true combination that secures the most perfect mutual dependence of the means involved, as well as affording a two-fold plan of control and operation both on the locomotive and the track at traffic control points, that acts on a common mechanism, to wit, the electro-magnet governing means 10 and which is governed by the control of a given track circuit.

The objection ordinarily offered to the employment of an open circuit means in this art, is that a broken conductor might 15 continue undetected and result in a danger giving condition. In the present invention, however, in that branch of the system employing a normally open control circuit provision is made in the event of a conductor 20 for thereof becoming broken, of relying upon the mechanically operated means or circuit-breaker for producing a danger indication and the application of the brakes, thereby revealing the failure of the broken conductor 25 or on the side of safety.

For the successful employment of duplicate electrical means or agencies on a locomotive, it should be designed so that the derangement of one circuit member will not 30 cause the derangement of the other circuit member, while both should be protected from injurious effects due to a "grounding" of the head-light circuits on a locomotive.

Therefore it is a further object of the 35 present invention to so combine the co-ordinate circuit members of the system, by making one of them normally active, while the other remains inactive until it reaches a traffic control point, where under safety 40 conditions, it is rendered active but for the moment, so that in the event of one of the circuit members becoming "grounded" it cannot dangerously affect the other circuit member because the fugitive current therefrom 45 would simply reinforce that of the other circuit member and aid in its functioning.

A further object of the present invention is to increase the precautionary measures 50 for safety by providing on four occasions, in a given block or section, for the transmission from the track of a control or operative impulse to the apparatus on the locomotive, in accordance with the condition of the block ahead, as well as providing under 55 danger conditions for the reduction of speed and gradual stoppage of the train, by inaugurating a progressive service application of the air brakes within braking distance of the block ahead and continuing the 60 brake application in the manner or natural order that would ordinarily be followed by an engineer in the face of danger.

It is further an object of the present invention to depend on electric power that 65 comprises two traveling sources of electric

energy, carried by the locomotive; the current from said sources may or may not differ in character, and to that end to employ a low voltage source of electric current, as a small storage battery in connection with 70 one portion of the dual system, and limiting it to its proper and economical field of usefulness in supplying current to low voltage signal lamps and electro-magnets, and to utilize, intermittently and momentarily, 75 in the normally inactive circuit member, under safety conditions, when it is completed, a higher voltage current, that is preferably furnished by the head-light turbo-generator, upon such occasions, thereby reducing 80 with vast economy the cost of the power factor, over the plan that depends upon current collection from track sources, at every block section along the line.

Electrical apparatus carried on a locomotive is subjected to heavy jar and vibration and the electrical conductors employed in conduits thereon do not have sufficient insulation strength to withstand the wear due to the effects of jar and vibration, for any 85 great length of time.

A further object of this invention is to provide a suitable and reliable means for revealing the insulation breakdown and "grounding" of conductors in any circuit employed in this system, which is a matter of 90 vital concern in a system of this kind.

Another object of the present invention is to provide a system having the above noted 95 characteristics, which shall, while being relatively simple as regards its parts and their arrangement, require but small cost to install and maintain it in operative condition, while at the same time it is certain and positive as regards its operation.

Those objects and features of my invention which have not been particularly and separately mentioned in the foregoing preamble will clearly appear in the light of the following more detailed description of 110 my invention embodied in the combined subsystems, which I have illustrated in the accompanying drawings.

As the present description of the dualistic system of train control does not relate so 115 much to the structure of the operating mechanism as to the organization and manner of control of the circuits involved, such means will be mostly shown diagrammatically in the accompanying drawings.

Referring to the drawings,—

Figure 1, is a general circuit diagram, illustrating both circuit members of the composite system united in working relation to each other, when brought into operative relation with a traffic controlling point.

Figure 2, shows an enlarged and detailed view of coils 7—8, of the magnet governing means, and the circuit connections thereof.

Figure 3, illustrates diagrammatically one form of track equipment required at the "home" and "approach" points, respectively, on a double track line.

5 Figure 4, shows a modified form of track equipment.

Figure 5, illustrates the structure provided in the truck insulation and the circuit arrangements depended upon to reveal insulation breakdown in the truck insulation and that of the conductors leading thereto.

10 Figure 6, shows an enlarged view of coils 7-8, of the governing magnet, illustrating the manner of employment of a second armature thereon for revealing failure of coil 8.

15 Like characters of reference indicate corresponding parts in the several figures, while the arrow in Figure 1, shows the normal direction of traffic for such an equipped line.

20 The purely electric branch of the dualistic system, constituting the instant invention, is generally the same, structurally and operatively considered, as that described in 25 the reissue patent aforesaid, and may be briefly described as follows:

25 Referring to Fig. 1 of the drawings, r , r' represent the rails of the track, which is divided into sections or blocks by the usual 30 insulating joints j , j' , each section including a source of current T , bridging the rails at the remote end, and a relay TR bridging the rails at the entrance or near end of the section, each relay being normally energized 35 and the armature thereof closing a loop w , w' , of negligible resistance, bridging the insulated joints between the rails of adjacent blocks or sections. As indicated, the current supply for the track circuit of each 40 block or section comprises a transformer T connected with mains TI , which supply alternating current from a generator or generators located conveniently to the roadway, thereby eliminating the trouble and expense 45 of maintaining local track batteries in each block.

50 Mounted on the locomotive are the control and working circuits, with their appropriate translating devices, supplied from a common battery 6, the control circuits, having coils 7 and 8 of the differential relay DR , which latter controls the working circuit, being indicated by reference letters A and B, respectively; the working circuit, including the valve holding magnet VHM , is represented by reference letter C; and the signal, or indicating circuit by D, the several circuits A, B, C and D being connected in parallel with common battery 6 carried by the locomotive.

55 Circuit A starts from the battery 6 and passes by way of wire 6*, loop wire l , circuit breaker CB' , loop wire l' , wire 23 to forward truck FT , rail r' , loop w , w' , including armature of relay TR , rail r of preceding

block, rear wheels A^2 to the frame of the locomotive, indicated by dotted line A^3 , to conductor f grounded on the engine frame at fa , coil 7, wire 24, and wire 6—back to the battery 6. This particular circuit is effective when the forward insulated truck FT is entering one block, such as X , and the other wheels of the locomotive occupy the rails in the preceding block, such as Y , when the forward block X is clear. When the locomotive is wholly within a given block and the latter is clear, the circuit A will be closed between the insulated forward truck FT and the driving wheels of the locomotive by way of the rails r , r' , as will be understood. 70

75 The circuit B is as follows: battery 6, wire 6*, wire 20, including normally closed push button pb , coil 8 of relay DR , wire 22, and wire 6—back to the battery. A loop in this circuit, around the push button pb , formed by wires C^3 and C^4 , includes an air operated circuit breaker 92, controlled by the air release during the application of the brakes and also the contacts of a speed governing means 95 to effect the required reduction of the speed of the train after the air is released, before the system may be restored, by operating the push button pb . 80

85 Circuit C, which controls the valve holding magnet VHM , is from battery 6, wire 6*, loop wire l , circuit breaker CB' , loop wire l' , wire 13, stationary contact 10, armature contact 9, armature 12 and frame 12' of relay DR , wire 19, coils of valve 100 holding magnet VHM , in parallel, wire 14, resistance R' , wires 15 and 6—back to the battery. 95

90 The circuit D, which energizes the electric lamps L , or equivalent signalling or indicating apparatus, includes wire 6*, wire 18, lamps L , in parallel, wire 16, resistance R' , wires 15 and 6—to battery 6. 105

100 The system, as thus far described, is generally the same as that of the reissue patent aforesaid in structural arrangement and mode of operation, the only material variations therefrom being the inclusion of the loop wires l , l' , and the normally closed circuit breaker CB' in the circuits A and 110 C, and the loop C^3 , C^4 around the push button pb in circuit B, which latter controls coil 8 of relay DR , which loop includes the air operated circuit breaker 92 and the speed governor controlled circuit 115 breaker 95, which two circuit breakers prevent the reenergization of the coil 8 and the restoration of the system by the engineer operating push button pb , until the air brakes have been applied and the speed 120 of the train reduced to a predetermined point. 125

130 In the diagrammatic illustration of Fig. 1 of the drawing, the locomotive is shown as entering an unoccupied block or section X ,

in which the all-rail track circuit controls the track relay TR, the wheels of the forward truck FT are shown, for the moment, as just entering the block X, while the driving wheels of the locomotive, represented by A², occupy the rails of the preceding block Y. In order to prevent the wheels and axles of the forward truck FT, which latter is insulated from the engine frame, shortcircuiting the relay TR, the latter is so constructed as to be relatively sluggish in its action, as compared with coil 7 of relay DR, and, provided the speed of the train is not reduced below a certain minimum, say five miles an hour, the coil of said relay TR will not be deenergized to break the circuit A through the loop w, w', when the locomotive is in the position indicated, with the wheels of the forward truck entering the block X and the other wheels of the locomotive occupying the rails of the preceding block Y. As soon as the forward driving wheels of the locomotive engage the rails r, r', of the block X, the circuit A is completed between the forward truck and the driving wheels through the rails r and r'. The coil 7 of the differential relay DR, when energized, normally exerts a stronger influence on the armature 12, to hold the same in safety position, than does coil 8 of the relay when energized, as fully explained in said reissue patent.

As indicated, the track relay TR is energized by a source of electric current bridging the rails at the far end of the block, said current source being a transformer T similar to that supplying the rails of block Y, so long as the rails of the section are clear and intact, the armature of the track relay engaging contact k, which completes the loop w, w', and prevents the operation of the cab signal and the application of the brakes, when the equipped locomotive passes over the insulated joints in the rails separating the blocks. If the section or block X, which the locomotive is shown as entering, is occupied by a preceding train, or the all-rail track circuit is broken, or the rails r, r', are bridged by any means which would shortcircuit the current supply of track relay TR, the said track relay will be deenergized, whereupon the circuit A will be interrupted by the armature of the track relay disengaging contact k and the coil 7 of differential relay DR will be deenergized, coil 8 will immediately attract armature 12, thereby interrupting circuit C of the valve holding magnet VHM, causing the latter to release the air and apply the brakes and the current from battery 6, previously employed for energizing the valve holding magnet, will be diverted through the lamps L, bringing the latter to bright incandescence and thereby

giving a positive visual signal of the danger condition.

Each of the coils 7 and 8 of the relay DR is preferably wound to the same low resistance, so that, when the circuit A, 70 which includes the coil 7, is interrupted, the current in circuit B, including coil 8, is strengthened by reason of the interposition of the bridge wire ab between the circuits A and B, so that the coil 8 immediately attracts the armature 12 and effects the breaking of the circuit C of the valve holding magnet, with the results as aforesaid.

Coil 7 and the armature 12 of differential se relay DR may be designed, if desired, as a stick relay, as shown in Fig. 2, so that, if the contacts i'' and g' are opened, coil 7 can only be reenergized by closing a shunt or branch A' by means of a normally open 85 push button pb'' in said shunt. It will also be noted that, in the event that coil 8 fails to function, when the armature 12 is released by the interruption of circuit A through coil 7, the armature 12 will, nevertheless, function to break the circuit C at contacts 9 and 10, by reason of the fact that said armature is counter-balanced with a bias to effect this result.

In order to provide means for revealing 85 or indicating the failure of coil 8 to function, the differential relay may be modified to the extent illustrated in Fig. 3, in which the relay, as a whole, is indicated by reference DR', the said relay being provided 100 with a second armature 12', pivotally mounted on the frame of the relay on an axis at right angles to the pivotal axis of armature 12, so that the respective ends of armature 12' are in proximity to and in operative relation with the ends of the cores of the coils 7 and 8 without, however, interfering with the normal operation of armature 12. Armature 12' is electrically connected in series with armature 12 through 105 the frame of relay DR', and the end of said armature 12', cooperating with the core of coil 8, is normally attracted by said core to close contacts 9' and 10' carried by the coil and the proximate end of said armature 12'. 110 The extent of movement of said armature 12' is limited by a suitable stop, such as s' on the coil 7, which is engaged by the end of the armature 12' adjacent said coil 7, so that the control of said armature will be 115 maintained by the coil 8 so long as the latter is energized. When the contacts 9, 10, and 9', 10' are closed, the portion of the circuit C, traversing the armatures of relay DR', is from wire 13, contact 10, contact 9, 120 armature 12, frame of relay DR', armature 12', contact 10', contact 9', to wire 19, thence through the valve holding magnet, as hereinbefore described. Should coil 8 be deenergized, by accident or otherwise, arm- 125 a- 130

ture 12' will be attracted by coil 7 and the circuit C will be interrupted at contacts 9' and 10', thereby deenergizing the valve holding magnet, effecting an application of the brakes and the raising of the current value in the signal lamps L to bring them to bright incandescence.

As soon as the circuit of coil 8 is restored, armature 12' will be immediately attracted 10 by the core of the coil to again close the contacts 9' and 10', as the normal pull of the core of the coil 8 on the armature 12' will exceed the attractive force of the core of coil 7. The deenergization of coil 7 will 15 not affect armature 12', which will remain in position to close contacts 9' and 10', so long as coil 8 is energized.

As was the case in the system described in the reissue patent aforesaid, the resistance 20 R' in the common section of the parallel circuits C and D is so adjusted that the lamps L will normally burn at low incandescence, thus serving as a telltale signal that gives constant evidence of the integrity 25 of the circuits and the condition of this portion of the system. When, however, the circuit C, which controls the valve holding magnet, is interrupted, the value of the current in circuit D will rise and bring the 30 lamps to bright incandescence, thereby indicating a danger condition.

Because of the low internal resistance of circuit A, including coil 7, and the employment 35 of the bridge wire db between circuits A and B, the system will function reliably when the resistance in the insulated joints of the track, or in a leakage pathway about said joints, is as low as 4/10 of one ohm, and long before such a low resistance 40 is reached, the loop w, w', will, by reason of its overlapping relation with respect to the joint, short-circuit either the track relay TR in the corresponding block, such as X, or the source of electric energy in the 45 adjacent block Y, according to which of the rail joints j or j' breaks down to the marginal resistance indicated.

In order to limit or nullify the effect of 50 any foreign direct current, flowing from one track section by way of loop w, w' to the adjacent section or block, on the track relay TR in the latter section, an impedance coil i is bridged across the terminals 55 of the track relay, as indicated in Figs. 1 and 4.

It is obviously essential that the front truck of the locomotive equipped with the apparatus, as hereinbefore described, must be carefully and completely insulated from 60 the other portions of the locomotive, and an effective means to this end is illustrated in Fig. 5, in which FT indicates, diagrammatically, the lower center bearing casting forming part of the truck. The insulating 65 means consists of a series of alternate fiber

cups I and metallic cups M nested within each other and in the recess in the center bearing casting of the truck. This form of insulation may be applied readily to the standard types of locomotives without keeping 70 the latter out of commission for any material length of time and have proven entirely effective under the most trying traffic conditions. The side walls of the fiber cups I are preferably extended vertically 75 above the upper edges of the metallic cups M, so as to prevent the electrical bridging of the cups M, M by the lodgment of any foreign metallic substance thereon.

In order to clearly indicate the dual plan 80 of control and operation of the circuits A and C, involving the insulated truck circuit on the one hand, and the ramp system on the other, so that the two portions of the system will function simultaneously, or 85 either will perform its normal operation in case of failure of the other, the ramp controlled portion of the system and its association with the purely electric controlled portion of the system will now be described. 90

As hereinbefore indicated, the circuits A and C each include a branch or loop, comprising wire l, circuit breaker CB', and wire l', the circuit breaker serving to open and close the circuit between the loop sections, 95 l and l'. The circuit breaker CB' comprises a reciprocatory stem, having heads on its opposite ends, the upper head serving to close the loop circuit l, l' through a contact plate mounted on the support through 100 which the stem reciprocates; the wire l being connected to the stationary member or plate of the circuit breaker and the wire l' to the reciprocating stem. The movable and stationary contacts of the circuit breaker are 105 normally held in contact by a helical spring Sa surrounding the stem. Likewise mounted for reciprocatory movement and insulated from the engine frame, is a shoe S, having an upwardly extending stem da, 110 which is normally forced downward or toward the track by means of a helical spring s'', surrounding the stem da. The shoe S is so disposed as to engage ramps, such as R, R'', mounted on the side of the track, 115 which ramps have their upper or contacting surfaces of anticlinal form, so that, when the shoe engages the upper face of the ramp, it will move upwardly and downwardly in its traverse of the ramp, thereby 120 effecting the successive opening and closing of the circuit breaker CB' as each ramp is passed, the stem da of the shoe S engaging the stem db of the circuit breaker so that, when the shoe is moved upwardly the circuit breaker is moved in the same direction and when the shoe returns to its normal position, after disengaging a ramp, the circuit breaker will also automatically return to 125 its normally closed position. Preferably, the 130

upper end of the shoe S is normally separated from the lower end of the circuit breaker CB' by a sufficient distance to effect a short delay between the initial engagement of the shoe with a ramp and the opening of the circuit breaker CB'.

Preferably, each block or section is provided with two ramps R, R'', the upper conducting surface of each being connected 10 in series with a wire TL50, one end of which terminates in a contact h, which is normally closed by the armature of track relay TR, thereby connecting ramp track loop TL50 with the rail r of the adjacent block by way 15 of the loop section w'.

Electrically connected with the shoe S is a conductor 50, the other end of which is attached to the positive terminal of a source of electricity, preferably the generator G, 20 which supplies current to the head-light. The other terminal of the generator G is connected to a conductor, wound about the insulated conductor 50 and paralleling the same in a reverse loop, to constitute an insulation break-down indicator, as will be hereinafter described, the so-called detector loop being indicated by wires d and d'. The free end of the detector wire d' is connected to an electro-magnet E, the other terminal 25 of which is connected to a wire m provided with a terminal contact n, normally engaged by the armature ta of an electro-magnet or relay TM, the other end of said armature being grounded at G' on the locomotive 30 frame.

The circuit, as thus described, constitutes the so-called test or pick-up circuit, which is completed each time the shoe S engages a ramp, the complete circuit, under safety 40 conditions, being as follows; from the positive pole of generator G, through conductor 50, shoe S, surface conductor of ramp R or R'', loop TL50, contact h, armature of track relay TR, track loop section w', rail r, driving wheel A² of the locomotive, thence to the ground at G' on the frame, 45 armature ta, contact n, conductor m, magnet E, wire d', paralleling conductor 50, thence through the convolutions of wire d 50 back to the negative terminal of the generator G; the closure of this pick-up or test circuit is of relatively short duration, depending upon the time of contact between the shoe S and the surface of the ramp. 55 Obviously, instead of making the return connection from the magnet E to the negative terminal of the generator G through the so-called detector loop d, d', the indicated terminal of the magnet E may be directly connected to the negative terminal of the generator. It will be noted that the 60 completion of this test or pick-up circuit is dependent upon the condition of the track relay TR in the block ahead. Should this 65 block be occupied and the track relay TR

short-circuited, the test circuit aforesaid will be interrupted at the contact h.

The principal function of the test or pick-up circuit is to cause the armature K of the magnet E to assume or maintain the same 70 relation as the armature of the track relay TR. In other words, when the armature of the track relay TR is attracted and the track loop circuit w, w' closed, and the test or pick-up circuit is closed by the shoe S 75 engaging a ramp, electro-magnet E will pick up or attract its armature K, thereby closing a circuit from battery G through wire lc, including normally closed push button pb, lamps L' in parallel between sections of wire lc, coils of a magnet TM, thence through a holding magnet F in series with TM, thence to a spring contact h', armature K, wire o, back to the battery. It will be noted that the armature K 80 operates with the cores of magnets E and F so that, when the magnet E attracts armature K, it simultaneously closes the circuit through the holding magnet F, and this latter magnet holds armature K in its closed 85 position until the circuit is subsequently interrupted by operating the push button pb. The closure of this circuit through the magnet F also energizes trip magnet TM, which 90 attracts its armature ta and breaks the pick-up or test circuit at contact n, thereby 95 preserving the current from the generator G.

The purpose of the pick-up or test circuit is to determine, first, by a conductivity test 100 through the track loop TL50, the condition of the track circuit ahead and also to pick up the armature lever K and raise it to safety position, under safety conditions, by the 105 momentary flow of current from the generator G through said circuit, second, to close the holding circuit through magnet F and simultaneously break the test circuit by the 110 operation of trip magnet TM, and third, to close a shunt circuit to the loop l, l', included in circuits A and C, which latter include the coil 7 of the differential relay DR and the valve holding magnet VHM respectively, said shunt circuit including wire s connected to loop section l, finger t to armature K, contact k² cooperating with said 115 finger, and wire s² connected with loop section l'. This shunt circuit to the loop l, l', is closed before the circuit breaker CB' is 120 actuated and, therefore, serves to preserve the integrity of the circuits through the coil 7 of the differential relay and through the coils of the valve holding magnet, when 125 said circuits would otherwise be interrupted by the circuit breaker CB' when the latter is operated by the shoe S engaging a ramp to break the loop l, l'.

The operation of the ramp section of the system is as follows: When the shoe S engages the ramp R'' in block Y and block X is clear, the first effect is to close the pick- 130

up or test circuit between the shoe S and the surface of the ramp by way of test loop TL50, contact h , track loop section w' , rail r , wheels A^2 , and frame of the engine, to ground at G' thereon, etc., as hereinbefore described, thereby closing the shunt s , s^2 about loop l , l' and circuit breaker CB' before the latter interrupts the circuits A and C at the loop l , l' . This produces no change in the normal relation of the coil 7 of relay DR and the valve holding magnet VHM, but causes the lighting of the lamps L' to indicate that the circuits and apparatus of the ramp section are intact. The engineer breaks the circuit from battery 6 through the holding magnet F at push button pb' , thereby releasing armature K and breaking the shunt s , s^2 to loop l , l' . These operations are repeated when shoe S engages ramp R, located near the "home" point of block Y. When block X is occupied and track loop w , w' is broken at contact h and loop TL50 is broken at contact h , the engagement of shoe S with the ramp R'' is ineffective to close the test or pickup circuit, and shunt s , s^2 remains open, with the result that, when the continued upward movement of shoe S opens circuit breaker CB', the circuits A and C are interrupted by said circuit breaker interrupting the continuity of loop l , l' , the brakes are applied, lamps L light up, and coil 8 attracts and holds armature 12 to hold circuit C open until such time as said circuits A and C can be restored by operating push button pb to interrupt the circuit through coil 8 of relay DR, as hereinbefore explained. After passing ramp R'', the engineer operates said push button when the speed of the train has been automatically reduced, as described, thereby restoring circuits A and C. Upon reaching ramp R, the operations just described are repeated, and a second application of the brakes and operation of the signal lights L effected, and the train is either automatically stopped, or may proceed, under properly reduced speed and absolute control, into the advance block X by the engineer again operating push button pb to break circuit B through the coil 8, thereby restoring circuits A and C to normally closed condition. Thus it will be seen that the functioning of the ramp controlled section is wholly independent of the insulated track, or electric controlled, section and, if the latter fails to operate, the train will be effectively protected by the ramp section of the dualistic system, and, conversely, if the ramp section fails, the insulated track section operates. Should both sections fail, the brakes are applied and the train is stopped at once.

The two ramp and connected loop arrangement, as shown in Figs. 1 and 3, contemplates placing ramp R'' the full braking

distance back of the "home" signal point and is rendered effective by connecting the two ramps by a single wire, properly insulated and protected, which wire constitutes a portion of the loop TL50. It will be evident, therefore, that the wayside installation of the ramp section is not only inexpensive to install and maintain, but reduces liability to derangement and damage of this portion of the apparatus to a minimum. Also, because of the fact that the engagement between the ramps and the shoe S carried by the locomotive, is only of sufficient duration to effect the initial closing of the test or pickup circuit by contact between the shoe and the ramp, and second, to raise the shoe to open circuit breaker CB', it is possible to employ relatively short ramps.

The alternate mode of obtaining remote control through the double ramp installation in each block or section is that illustrated in Fig. 4, in which each block or section of the track is subdivided into two sections by means of insulated rail joints j^2 , j^3 , the rails of the subsection adjacent ramp R'' being represented by reference characters r^2 and r^3 , respectively. In order to render this form of installation effective, it is necessary to interpose a so-called repeater circuit, which will respond to and repeat the operation of the track relay TR in the next section ahead. The repeater circuit includes a battery X', one terminal of which is connected by conductor rd to finger hb of the track relay TR, which finger normally engages a stationary contact re , which in turn is connected with track loop section w to rail r' . The other terminal of the battery X' is connected to repeater relay LR, the other terminal of which relay is connected by conductor rc to rail r . So long as track relay TR is energized, the circuit through the repeater relay LR will be completed and the armature of said relay will be attracted. When the track relay TR is short circuited, the circuit of the repeater relay LR is broken at contact re and the armature of the latter relay falls away. The purpose of the repeater relay LR is to maintain the same operating conditions in the subsection of the block adjacent the ramp R'' as are maintained in the main section of the block, and also to maintain the integrity of the track circuit from the transformer T to the relay TR of the given block, such as X. To effect these results, the following connections are employed; the joint j^2 in one rail is normally bridged by a loop comprising wire ta , armature finger Z' , contact y' , and wire tb , and similarly, point j^3 is bridged by wire sc , armature finger Z , contact y , and wire sd . These bridging loops are maintained intact so long as repeater relay LR is energized. When, however, relay LR is deenergized by the short-circuiting of the track relay TR in the

- block ahead, it is also necessary to preserve the continuity of the track circuit in block X, which is effected by means of a conductor te connected to rail r and having 5 therein a suitable condenser g and ending in a back contact bc , engaged by finger Z of armature of repeater relay LR, when the latter is deenergized; and a second conductor td' , having a condenser g' and contact bc' 10 cooperating with finger Z' of the armature. Under the conditions just indicated, the complete track circuit is as follows: from one terminal of transformer T to rail r , wire te , contact bc , finger Z, wire sc , rail section r^3 , relay TR at the entrance of block X, rail r^2 , wire ta , finger Z' , contact bc' , wire td , rail r' , to the other terminal of the transformer T. The condensers g , g' will prevent the passage of direct current but will 15 allow the alternating current to pass freely to energize the track relay TR, so long as block X is unoccupied. The contact surface of ramp R'' is connected to rail r^3 as follows: wire sa , finger la of armature of relay 20 LR, contact v , wire sb , to rail r^3 , so that, when the shoe S of the locomotive engages ramp R'' , the test or pick-up circuit on the locomotive will be closed from the generator G (Fig. 1), wire 50, shoe S, ramp R'' , wire su , armature finger la , contact v , wire sb , rail r^3 , to engine wheels and frame, ground at G' to magnet E, back to generator G, the engine carried portions of the circuit being the same as those hereinbefore described. If 25 the advance block is occupied, relays TR and LR are deenergized, and the circuit last traced is broken at contact v , of relay LR, consequently, when the shoe S engages the ramp R'' , the test circuit will not be closed 30 and the circuits A and C on the locomotive will be broken at circuit breaker CB' , thereby causing application of the brakes and the bright illumination of the signal lamps L. When the ramp R is reached, the test or 35 pick-up circuit is completed as follows: generator G, wire 50, shoe S, ramp R, wire se connected to the contact surface of the ramp, armature finger la of track relay TR of the block ahead, contact h' , track loop section w , rail r' , engine wheels and frame, to ground at G' , magnet E, back to generator, as before. It will be apparent, therefore, that the employment of the subdivision of 40 each block adjacent the ramp at the approach point of the block and the interposition of the repeater relay circuit and the loop about the insulated joints between the track sections of each block will in no way interfere with the normal functioning of 45 the insulated track section of the system, or with the normal operation of the track circuit, including the source of alternating current T and the track relay TR in each block, but will, nevertheless, secure the certain and 50 reliable operation of the ramp section of the system either to close the pick-up or test circuit, as each ramp is engaged, to give a definite indication when the block ahead is clear, or, under danger conditions, to cause the circuits A and C to be interrupted when 55 each ramp is passed, by the normal operation of circuit breaker CB' , thereby causing application of the brakes and the lighting of the signal lamps L. 75
- As an ancillary protective means to indicate the failure of the insulation of any of the circuit wires, or the breakage of the wires, it is proposed to associate with all or any desired number of the circuit wires or conductors, detector loops, which, upon failure of the insulation or disruption of any conductor, will short-circuit the particular current source supplying said conductor. For example, in Fig. 1 the detector loop is 80 associated with conductor 50 between the generator G and the shoe S, which conductor is subject to heavy vibrations and strains, said loop comprising a conductor wire d wrapped or wound about insulated conductor 50 and then brought back in a loop d' 85 parallel to conductor 50 and lying adjacent to d , one end of wire d being connected to the negative terminal of the generator G and the opposite end of d' being connected to one terminal of magnet E of 90 the test circuit. Any serious impairment of the insulation on conductor 50, or a breakage of the latter, which would involve a contact with either wires d or d' , will be evidenced immediately by the short-circuiting 95 of the generator G between the conductor 50 and either one or both of loop sections d , d' . The same protective effect may be obtained with respect to the conductors supplied by 100 current from battery 6, by connecting the protective loop wire to one terminal of battery 6 and winding the wire about the particular conductors to be guarded, as illustrated in Fig. 5, in which wire d^2 is connected to the negative pole of battery 6 and wound in convolutions d^3 about conductor lc 105 in the holding circuit, thence continuing as loop d^4 paralleling wire lc , whence it is passed in successive windings or coconvolutions as d^5 about loop wires l' and l , thence 110 paralleling conductor 23 in a section d^6 and connected to one or more of the metallic cups M of the truck insulation, whence a final section d^7 is wound about conductor 23. The failure of insulation of any of the wires 115 associated with the conductor loops will be evidenced at once by the short-circuiting of the battery 6 and the release of the brake holding magnet, which would apply the brakes. It will be understood, of course, 120 that similar protective loops may be applied to all of the circuit wires involved in the system but, as the wires or conductors here-tofore referred to are the principal ones 125 which are liable to damage or impairment, 130

under normal conditions of use, the protective loops have been indicated as applied only to such wires or conductors.

From the foregoing description, it will be apparent that the instant invention involves a simple and reliable dualistic system of train control, in which both elements of the system will be effective to accurately and reliably indicate safety conditions at all times, that will with equal reliability and effectiveness cooperate to indicate danger conditions and first reduce the speed of the train and then automatically stop the same, under danger conditions, unless the engineer assumes control after the desired reduction in the speed has been made, each of the separate elements of the dualistic system being so far independent of the other as to function perfectly in the case of failure of the other. In case both elements fail, the train will be automatically stopped.

What I claim as new, and desire to secure by Letters Patent, is—

1. The combination with a train carried electro-magnet governing means, of a normally closed circuit therefor, and a series of all-rail track circuits, a dual system of control and operation interposed between said track circuits and said electro-magnetic governing means to act on said magnet governing means, one system operating according to an electrical mode of operation and the other according to an electro-mechanical mode of operation and both responding under the influence of a given track circuit.

2. A plurality of all-rail track circuits arranged in immediate relation to each other, a normally closed circuit carried by a vehicle movable on the rails, including the rails and a track loop of negligible resistance at a predetermined point and directly controlled by the adjacent track circuit, a second closed circuit including vehicle control mechanism controlled by the first mentioned circuit, a normally open circuit carried in part by the vehicle and in part by the trackway and including the rails and the track loop aforesaid, and means carried by the vehicle for closing said open circuit at a predetermined point to first establish an alternative closed path for said second closed circuit and then to interrupt the original path of said second circuit under safety conditions.

3. A plurality of all-rail track circuits arranged in immediate relation to each other, a normally closed circuit carried by a vehicle movable on the rails, including the rails and a track loop of negligible resistance at a predetermined point and directly controlled by the adjacent track circuit, a second closed circuit including vehicle control mechanism controlled by the first mentioned circuit, a normally open circuit carried in part by the vehicle and in part by the trackway and including the rails and the track loop aforesaid,

said, a mechanical circuit breaker in said second circuit, and means carried by the vehicle for closing said open circuit at a predetermined point to close a shunt around said circuit breaker to maintain the integrity of said second circuit and then to operate said circuit breaker to interrupt the original path of said second circuit under safety conditions.

4. The combination with a vehicle carried normally closed circuit, and an electro-magnet governing means included therein, of a normally closed track connected control circuit operatively associated with the first mentioned circuit, an all-rail track circuit, a point of resistance on the track that is presented to and withdrawn from the control circuit, under the influence of the track circuit, track engaging mechanically operated means for breaking the first mentioned circuit, and a normally open vehicle carried circuit associated in controlling relationship with the first mentioned circuit and controlled by the track circuit under safety conditions to close the first mentioned circuit against the mechanically operated means.

5. The combination with a vehicle carried normally closed circuit, and an electro-magnet governing means included therein, of a normally closed track connected control circuit operatively associated with the first mentioned circuit, an all-rail track circuit, a point of resistance on the track that is presented to and withdrawn from the control circuit under the influence of the track circuit, track engaging mechanically operated means for breaking the first mentioned circuit, a normally open holding circuit, and a normally open control circuit co-operatively associated with the first mentioned circuit and controlled by the track circuit under safety conditions to close the first mentioned circuit against the action of the mechanically operated means.

6. The combination with a vehicle carried normally closed circuit, and an electro-magnet governing means included therein, of multiple control means operatively associated therewith, embracing a normally closed control circuit, a normally open controlling circuit and a mechanically operated means interposed between the first mentioned circuit and the track, an all-rail track circuit, controlling devices at traffic control points governed by the condition of the track circuit for opening said normally closed circuit through one of said controlling devices and separately opening the same through the action of the mechanically operated means under danger conditions both of said controlling circuits co-operating under safety conditions to maintain the first mentioned circuit closed under the influence of the track circuit against the action of the mechanically operated means.

7. An automatic train control system of

a dualistic character having in combination with a normally closed circuit an included electro-magnet carried on a vehicle, of mechanically operated means for opening 5 said circuit, embracing members along the track and a member carried by the vehicle disposed in running position to engage said track members, an all-rail track circuit, vehicle carried control circuits interposed between the first mentioned circuit and the 10 track circuit and controlled by the latter at predetermined points one of said control circuits under safety conditions holding closed the first mentioned circuit while the 15 other under like conditions automatically places a compensating shunt on that portion of the first mentioned circuit about to be broken by the mechanically operated means.

8. In a dualistic train control system, a 20 vehicle carried working circuit and a co-operatively associated control circuit both of which are responsive to a cessation of current said control circuit having two sets of normally closed terminals arranged in series, 25 one of said sets being vehicle carried while the other is arranged in operative relation to the track, means depending upon the movement of said vehicle to open said terminals under danger conditions at predetermined points, a loop of negligible resistance for bridging each of said terminals under safety conditions to form a compensating pathway, a vehicle carried transient circuit for controlling the loop for bridging the 30 vehicle carried terminals, an all-rail track circuit for controlling the transient circuit and the other loop to render inoperative the working circuit under safety conditions.

9. In a dualistic train control system, a 40 vehicle carried working circuit and a co-operatively associated control circuit both being responsive to a cessation of current said control circuit having two sets of normally closed terminals arranged in series in the 45 control circuit one of which is on the track and the other on the vehicle, means depending upon the movement of said vehicle to open the terminals of both under danger conditions at predetermined points, an all-rail track circuit, and partial circuit devices controlled by the track circuit for providing a compensating pathway for the respective sets of terminals under safety conditions to render the working and control circuits 50 unaffected under safety conditions, at such points.

10. In a dualistic train control system, a vehicle carried working circuit and a co-operatively associated control circuit, both 60 being responsive to a cessation of current, said control circuit having included at three different points circuit making-and-breaking devices two of which are vehicle carried while the other is arranged in direct operative relation to the track, one vehicle carried 65

circuit making-and-breaking device and that in operative relation to the track being opened by the movement of the vehicle past a given point in the track under danger conditions, an incomplete transient control circuit extending substantially in parallel relation with the first mentioned control circuit and that is responsive to closure to cause the closure of the other vehicle carried making-and-breaking device, and an all-rail track 70 circuit for controlling the closure of the transient circuit and the breaking-and-making device arranged in operative relation to the track under safety conditions. 75

11. In a dualistic train control system, a vehicle carried working circuit and a co-operatively associated control circuit both being responsive to a cessation of current said control circuit having two sets of normally closed terminals arranged in series one 80 of which is vehicle carried while the other is arranged in operative relation to the track, means depending upon the movement of the vehicle to open said terminals at predetermined points, a transient co-ordinate control 85 circuit responsive to closure thereof to insert a low resistance shunt across the gap of the vehicle carried terminals, a track loop for closing the transient control circuit and the track connected terminals of the first mentioned control circuit, and an all-rail track circuit for controlling said track loop, the whole arranged to render the first mentioned control circuit and the working circuit inoperative under safety conditions. 90

12. In a dual system of train control, a cab carried working circuit and a co-operatively associated control circuit that is track connected, both of said circuits having a common source of electric energy and working on the closed circuit principle, and another control circuit co-operating with said working circuit that is fed by a different source of electric energy and possesses a different character of operation, a mechanically operated means for breaking said working circuit and a fixed member on the track for actuating said mechanically operated means, and an all-rail track circuit for simultaneously controlling said control 105 circuits to hold the working circuit closed against the action of the mechanically operated means under safety conditions. 110

13. In a dualistic train control system, a plurality of all rail track circuits, each including an insulated track section, a source of current and a relay; a control circuit carried by the vehicle; partial circuit devices co-operatively associated with the track and directly controlled by said relay to determine 120 the condition of said control circuit; a second circuit on the vehicle normally maintained closed by said control circuit; and train control mechanism rendered operative 125 upon cessation of current in any of said circuits 130

cuits, in combination with a normally incomplete transient control circuit, partial circuit devices therefor co-operatively associated with the track circuit and directly controlled by the track relay to determine the condition of the first mentioned control circuit and the second circuit.

14. In a dualistic train control system, an insulated track section, a source of electric energy and a relay; a control circuit carried by a vehicle; partial circuit elements for opening and closing said circuit that are directly controlled by said relay; a second circuit on the vehicle normally maintained closed by said control circuit; and train control mechanism made operative upon cessation of current in any of said circuits, in combination with a mechanical circuit maker-and-breaker that engages a part on the track at predetermined points for the opening of the second circuit every time the said breaker engages a part on the track, a normally incomplete transient control circuit carried on the vehicle, a partial circuit therefor co-operatively associated with the track relay to determine the condition of said circuit, and means controlled by said transient control circuit for inserting a compensating shunt across the break about to be effected in the second circuit by the circuit breaker under safety conditions, and a third signal and holding circuit that is initially closed under the influence of the transient control circuit and the track relay for maintaining said compensating shunt in closed position.

15. A railway cab signal and control system, comprising a signal and brake controlling circuit, a source of electric energy therefor, an all-rail track circuit, and means comprising two independently operating circuits interposed between said track circuit and the first mentioned circuit that are controlled by the track circuit to maintain the integrity of the first mentioned circuit under safety conditions at traffic control points, and a mechanically operated means and a point of resistance operating respectively to effect an opening of the first mentioned circuit under danger conditions.

16. In a dualistic train control system, an insulated track section, a source of current and a relay, another source of current and a control circuit carried by the vehicle, partial circuit elements co-operatively associated with the track section and directly controlled by said relay to determine the condition of said control circuit; a second circuit on the vehicle normally closed through the control circuit; train control mechanism rendered operative upon the cessation of current in any of said circuits, in combination with a mechanical circuit maker-and-breaker, a fixed member along the track for engaging and operating the latter during the movement of the vehicle to open the second cir-

cuit every time it passes said point, a second source of current on the vehicle, a vehicle carried partial circuit co-operatively associated with the relay to complete said circuit with the inclusion of the second source of current under safety conditions said partial circuit being responsive under closure to effect a shunt around the point in the second circuit subject to the mechanical breakage before it is effected, and a holding and signal circuit in parallel with the first two mentioned circuits that is fed by the first mentioned source of current which is established by the partial circuit under safety condition through the influence of the track relay.

17. In a dualistic train control system, a normally closed working circuit, a signal and train control mechanism rendered operative upon cessation of current in said working circuit, a normally closed control circuit for determining the condition of said working circuit, a mechanical make-and-break device for breaking and making the working and control circuits, a fixed member along the track for operating the device to break the working and control circuits every time the fixed member is encountered, a normally open control circuit responsive to closure to effect a compensating shunt across the break effected by the mechanical circuit breaker to preserve the integrity of the working circuit, a signal and holding circuit that is closed upon the closure of the open control circuit to retain the compensating shunt when established, an all-rail track circuit having a source of electric energy and a relay, and partial circuit devices co-operatively associated with the track circuit for determining the condition of the normally closed and normally open control circuits respectively.

18. The safety system for railway trains hereinbefore described, comprising two train carried co-ordinate circuit members, a track circuit from which they are disconnected under danger conditions and to which they are connected under safety conditions at predetermined points, a normally closed brake control circuit carried by the train controlled respectively by said co-ordinate circuit members, a mechanically operated means interposed between said brake control and track circuits that acts to mechanically break said control circuit when said co-ordinate circuit members are disconnected from the track circuit under danger conditions and means associated with one of said co-ordinate circuit members to maintain the other coordinate circuit member closed against the action of the mechanically operated means under safety conditions.

In testimony whereof I affix my signature.
JOSEPH WHITMAN BUELL.
